BANDING AND WRAPPING MACHINE

Francis X. Malocsay, Upper Saddle River, N. J.,
assignor to International Banding Machine
Company, a corporation of New York

Application August 11, 1934, Serial No. 739,363

11 Claims. (CL. 93—2)

This invention relates to the art of applying advertising media to cigars and more particularly to the wrapping of transparent wrappers around cigars so that the advertising is visible therethrough.

It is among the general objects of the present invention to provide an improved mechanism of the character hereinafter described, which will be entirely automatic in its operation.

One of the objects of my invention is the combination in a machine of the class herein described, having a cigar conveyor with means for applying a plurality of advertising media at different positions on a cigar, and provided with means for applying a transparent cellulose wrapper to a cigar so that the advertising medium is visible therethrough.

In one of my previous applications, for example, in the Wrapping and banding machine described in Serial No. 653,609, filed January 26, 1933, separate band and wrapper feed mechanisms were located at the rear of the machine, a wrapper being advanced by the feed rollers to a position underneath the band magazine from which a single band was placed upon said wrapper, whereupon a reciprocating mechanical gripper carried both band and wrapper to a position beneath the wrapping and banding device, and over a cigar which is raised from underneath into said combined wrapper and band, carrying them upwards into the banding and wrapping position properly. When in this stationary position, the wrapping, banding and sealing operations are performed, and the band will appear on the outside of the cigar wrapper, encircling the same.

The present invention has a similar arrangement, insofar as the band and wrapper feeding devices are likewise installed at the rear of the machine, both to one side of and at right angles to the rectilinear cigar feeding and delivery path to which both devices feed a wrapper and band simultaneously, but in two essential features it differs from the machine referred to, viz: in that the band is fed in such a way that it goes underneath the wrapper, between the cigar and the wrapper, so as to be visible therethrough, and secondly, that the feeding is performed, not by any mechanical gripping appliance, but by pneumatic suction, applied not only for picking the band from the stack of bands in the reservoir provided for this purpose, and placing it into the course of the wrapper feed, but likewise for transporting both wrapper and band simultaneously to the wrapping and banding position.

In another copending application, Ser. No. 713,116, filed February 27th, 1934, I have described a band and wrapper feeding apparatus, which has several operative mechanisms and features in common with the present invention, and reference will be made to this application and its parts in the proper places. One feature common to both is that the band and the wrapper are fed in the same relation to the cigar; that is, the band is placed between the transparent wrapper and the cigar, but in two essentials this other apparatus, referred to, differs from this invention as well as from the first mentioned device described under Ser. No. 653,609, as follows: While the wrapper feed rollers are located at the rear of the machine, the band magazine and the band feeding device are positioned on the opposite or front side of the machine, separated from each other by the cigar feeding and delivery path toward which both devices feed a wrapper and a band from opposite ends. Secondly, while the picking of the band from the magazine stack is done by pneumatic means, the transporting of the band and wrapper together toward the wrapping and folding mechanism itself is performed entirely by mechanical means, though these means differ in detail very much from the mechanical gripper appliance used in the first mentioned device described under Ser. No. 653,609. In addition to the differences set forth already, the present invention differentiates from both these machines and other previously described or patented devices by some peculiar and novel functions and accomplishments presently to be described.

It is often desirable and has become a practice to label the cigars not only with the usual ornamental cigar band or medallion or panel, but also with a small label or the like to bear the name of the maker or a trademark or the date of manufacture. In some cases this could of course be printed upon the transparent wrapper, but it would be much more convenient if a little separate tag could be applied in a suitable manner to either the cigar or the wrapper, so that the regular blank wrapper, which comes in rolls, could be used without any previous preparation or printing thereon. The present invention solves this task. It makes it possible to either apply two bands and a wrapper to a cigar, or one band and a label, which latter is attached to the inside of the transparent wrapper only, or, if desired, two labels, attached to the wrapper so that the same may be visible therethrough.

For economical reasons, a further modification

10

55

may be made where the center portion of the band, that is, the medallion, is to be applied to the underside of the wrapper, either alone or besides a small label or tag. Then the medallion as well as the label is firmly attached to the wrapper and is removed with the wrapper, while in the usual method the cigar band remains on the cigar.

By using the center portion or medallion of the band only, a decided saving of material is effected, for it is obvious that the amount of paper and material commonly used in printing one band will now produce at least two center portions and two tags or labels, thereby effecting a saving of at least 50% in the cost of manufacturing and also provide a more attractive package.

These medallions or labels can furthermore be printed in continuous strips or rolls, which means a greater saving and facilitates their handling. Another advantage, not to be overlooked, is the appearance of the package and the advertising facilities it offers.

The fastening of a single cigar band was effected in the former machines in a cold way; i. e., by a moistening device as described in the application under Ser. No. 713,116, which wetted the adhesive substance with which one end of the band was impregnated, but it is apparent that it would be more complicated and difficult to attach a single very small label securely to the inside of a transparent cellulose wrapper (which furthermore does not take any moist adhesive so well) by similar means, and therefore this invention has for its aims to attach such labels or medallions to the wrapper in a different way, namely by a heating device.

It is among the objects of the present invention to provide a band and wrapper feed arrangement wherein a band magazine and a label receptacle are provided near the delivery path of wrapper feeding device and adapted to intermittently feed a single band or medallion and a single label simultaneously into alignment with the wrapper path, to be conveyed along in unison with a separate cut-off wrapper.

Another object of my invention is to provide pneumatic suction means whereby said band, as well as said label, are picked from the bottom of stacks held by the band magazine and the label receptacle respectively, one of each at the same time, and transferred by the same suction means to the path of the advancing wrappers.

A further object of my invention is to provide means whereby the label and the band are both placed underneath the cut-off and advanced wrapper portion and after reaching their correctly adjusted position, are temporarily held and supported in such position.

A further object of my invention is to provide adjusting means whereby the label may be positioned and held underneath the wrapper sheet in different optional ways and at different angles.

Another object of my invention is to provide means whereby said label, when correctly arranged underneath the wrapper, may be fixedly and permanently attached to the latter.

Another object of my invention is to provide heating and pressing means whereby the spot on the waterproofed transparent cellulose wrapper under which the label is placed is softened and the latter is firmly attached to it by pressure.

Another object of my invention is to impregnate the face of the medallions or labels to be attached to the wrappers with a lacquer or coat-

ing which becomes adhesive by heat so that it firmly sticks to the wrapper pressed against it.

A further object of my invention is to provide reciprocating conveying means adapted to transport the band together with the superimposed wrapper and the label, now firmly attached to it, to a wrapping and banding position.

Another object of my invention is to provide pneumatic gripping means for said conveyor so that both the band and the wrapper are firmly held in place during the transport by a sucking action.

A further object of my invention is to provide a novel actuating mechanism for the reciprocating wrapper, band and label conveyor, said actuating mechanism including means to optionally and adjustably limit the travel of the conveyor.

Another object of my invention is to provide means whereby the movements effecting the transfer of the band and the label to the conveyor, which carries them together with the wrapper to the wrapping and banding mechanism may be synchronized with the working phases of the latter so that they work together in alternating and continuous cycles.

A further object of my invention is to provide controlling means for the air ducts of the picker devices as well as the pneumatic conveyor so that the alternating shut-offs and openings in the suction passages may be synchronized with the working phases of the whole feeding and wrapping operations.

Other more specific objects and advantages of the apparatus will appear as the nature of the improvements are better understood, the invention consisting substantially in the novel arrangement and correlation of instrumentalities herein fully described and illustrated in the accompanying drawings wherein similar reference characters are used to describe corresponding parts throughout the several views and then finally pointed out and specifically defined and indicated in the appended claims.

The disclosure made the basis of exemplifying the present inventive concept suggests a practical embodiment thereof, but the invention is not to be restricted to the exact details of this disclosure, and the latter therefore is to be understood from an illustrative, rather than a restrictive standpoint. It will be understood that the various features of the invention disclosed may be separately applicable despite their cooperation herein shown.

The invention may be more fully understood from the following description in connection with the accompanying drawings, in which—

Fig. 1 is a top plan view of my improved band, label and wrapper feed arrangement, showing part of the cigar feeding and discharge table, the wrapper feed mechanism on the left or rear side of the table, and the band and label supplying mechanism in between them. The wrapper roll supported on the feed rollers on the left side is omitted, and the wrapping mechanism above the table is also not shown, only the gripping jaws of the latter being indicated in a diagrammatical way. Other parts of the wrapping and delivering apparatus, being old and forming no parts of the claimed improvements, are also left out.

Fig. 2 is a partly sectional elevation, taken along the line 2—2 of Fig. 1, looking toward the delivery end of the machine, and showing the wrapper roll and feeding mechanism in elevation, the label

and band transfer apparatus, the label and band magazines and part of the heat-sealing device in front view and the wrapping and banding mechanism only indicated in dot and dash outlines.

5 Fig. 3 is a rear elevation of the band and label transfer mechanism, taken along line 3—3 of Fig. 1, the wrapper feed mechanism together with the cut-off device being removed. The actuating lever mechanism for the transfer spindles or 10 pickers is shown in part; i. e., as far as it extends toward the delivery end of the machine.

Fig. 4 is a partial top view of this portion of the actuating lever mechanism, placed in proper relation to the corresponding parts, shown in elevation below.

15 Fig. 5 is a continuation of Fig. 3, showing the rest of the actuating lever mechanism for the band and label pickers, as far as it extends toward the cigar feed or hopper end of the whole machine.

Fig. 6 is a sectional view, taken approximately along the line 6—6 of Fig. 1 through the main frame and the lower part of the machine, showing the reciprocating conveyor for the wrapper and 25 band and its actuating mechanism in elevation. It also shows part of the wrapper feed actuating mechanism. The other part can be seen in Fig. 1. The conveyor carriage is shown in its starting position when it receives the wrapper together 30 with the band and the label. Other parts of the machine, not directly pertinent to the conveying device, are not shown, so as not to obstruct the clearness of illustration.

Fig. 7 is a top view of the reciprocating conveyor and its guiding and moving parts.

Fig. 8 is a section at an enlarged scale through the conveyor carriage, showing part of its guide bar and actuating chain. The carriage is shown in its end position, ready to release the wrapper 40 and band.

Fig. 9 is a top view of the band and label pickers showing them in the receiving position; i. e., picking up a band and a label simultaneously by suction.

45 Fig. 10 is a similar view, showing the pickers in the transferring position; i. e., delivering a band and a label at the same time into a position underneath the supporting plate which carries the cellophane wrapper.

50 Fig. 11 is an elevation of the pneumatic suction head inserted into the picker arm which transfers the label.

Fig. 12 is a section through the pneumatic suction head, inserted into the picker arm which 55 transfers the cigar band.

Fig. 13 is a side elevation of the heat-sealing device, shown separately and partly in section.

Fig. 14 is a top view of the heat-sealing die, inserted into the head of the aforesaid heat-sealing device.

Fig. 15 is a top view of the label magazine base. Fig. 16 is a side view of the same.

Fig. 17 is a modified arrangement of the platform shown in Fig. 1, carrying the magazines, but instead of having a band magazine, it has a modified magazine for medallions.

Fig. 18 shows a wrapper with a cigar band underneath it and a label in a longitudinal position. The position of the cigar before being wrapped is likewise indicated in dot and dash lines.

Fig. 19 is a similar view, showing a medallion over a cigar and a label in a diagonal position.

75 Fig. 20 is another illustration of a wrapper

with a medallion and a label placed across the cigar.

Similar characters denote similar parts throughout the different views.

Referring more in detail to the figures listed, Fig. 1 shows a partial top view of the table or frame 1, supporting the various mechanisms, as described before.

Character W designates the wrapper feed, XY 10 the band and label feeding device, C the cigar feed, D the wrapping and banding station and S the heat-sealing device. The cigars are fed in a continuous row from the hopper, not shown in the drawings, but located at the lower end of the table 1 (below what is shown in the drawing of Fig. 1). The type of this mechanism is fully described and illustrated in my former Patent No. 1,653,641, filed December 27, 1927, as also in the copending applications, Ser. No. 492,437 (Cigar banding machines), filed October 31, 1930, as well 15 as in Serial No. 519,347 (Cigar handling machines) filed March 2, 1931. From this hopper the cigars are fed into a belt feed, part of which is shown at the top of Fig. 1. This belt feed advances the cigars with an intermittent movement, the rest periods between the forward movements of the cigars being equal to one complete cycle of operations necessary to complete the wrapping and banding of a cigar by the machine. Then 20 the cigars are pushed one by one upon the top of a cigar elevator or plunger where they are covered by the combined band and wrapper, supplied to this location by the communicating conveyors. This location of the cigar is indicated in 25 Fig. 1 at D by dotted lines, and vertically above this is installed the wrapping and banding mechanism, into which the rising plunger carries the cigar, folding at the same time the band and the superimposed wrapper around the three 30 exposed sides of the cigar. This wrapping and banding mechanism is not shown in Fig. 1, except that the gripper jaws are diagrammatically indicated in section at D, but its contour is indicated by dot and dash lines in Fig. 2. The 35 details of the construction and operation of the wrapping and cigar conveying mechanism, and also the remaining parts of the whole machine; i. e., the parts belonging to the drive or the delivery of the wrapped and banded cigars, as far as 40 they are not altered and described in their modified form in this specification, can be learned 45 from my copending application, Ser. No. 653,609 (Wrapping and banding machine), filed January 26, 1933. Details of the intermittent belt feed 50 and the centering means whereby the cigar, before it is moved into its band and wrapper, is 55 exactly adjusted so as to meet the band and wrapper in the proper place, may be learned more especially from the copending application, Serial 60 No. 715,124, filed March 12, 1934.

The wrapper feeding device

This device is illustrated mainly in Figs. 1 and 2 while a part of the drive for it is shown in Fig. 6. Principally it resembles the corresponding device, described and shown in the aforementioned application, Ser. No. 713,116, although in the present case it is shown in a somewhat simplified form. The only important change concerns the wrapper cutting device, that is: the knife 110 which for obvious reasons does not have to be an undercutting knife in this case, but cuts the wrapper strip from above, as was done already in former devices shown by me. 75

As for the special construction of the wrapper feed itself, no novelty is claimed and the above mentioned specification may largely be referred to for special information about its details, a short summary of the pertinent former description may suffice while, to facilitate comparison, the same numerals are used in both cases.

A loose cellophane roll W (Fig. 2) of a width corresponding to the required wrapper for the special kind of cigars handled is supported by a pair of roller sets, as shown in Figs. 1 and 2. The first set comprises the central pulley 101, fixedly attached to the shaft 100 and the adjustably mounted, flanged rollers 102. Swivel screw 103 keeps them in adjusted position. The second set comprises the supporting roller 57, provided with two rubber tires 92, spaced so as to guide the outer edges of the cellophane strip. This roller can turn freely on the shaft 59, but fixedly connected therewith is a spur gear 98, which is in mesh with a similar spur gear (not shown) underneath it, on the driving shaft 58 (see Fig. 2). On the latter is fixedly secured a roller 56, which is in adjustable potential contact with the rubber tires 92, as explained more in detail in the aforementioned specification. On this shaft is also mounted the clutch 62 which is of the free-wheeling type, adapted to intermittently turn the driving shaft only in one direction; i. e. clockwise, when looking at Fig. 2, and the sprocket 18, fixedly mounted on the freely rotatable hub of the clutch cup. This sprocket is rotated in alternate directions by the chain 79 which with one end is attached to a stud 81 in a spring drum 80, mounted separately and independently from the roller shafts on a stud 82 on the frame 55 see Fig. 1. The details of this drum and clutch are minutely described in the aforesaid specification to which attention is called, but it is apparent from the present summary description that if the sprocket is turned reciprocatingly, as will be further explained when the wrapper feed drive is described, the clutch will impart intermittent impulses to the drive shaft 58 and through the intermediation of the spur gears also to the shaft 59. The cellophane sheet, unwinding from the bottom of the roll, travels around rollers 101, 102, glides along plate 71 which is fastened to the frame 55 that supports the roller bearings, in which shafts 100, 59, and 58 are journaled, and is fed by friction between the feed rollers 51 and 56 toward the knife mechanism 110. By means of the clamp bolt 123, the frame 55 may be adjusted in its relation to the rest of the machine. All other implements and adjusting means of this wrapper feed device may be learned more in detail from the copending specification, Ser. No. 713,116, but they are immaterial, as far as any novel features, claimed for this invention, are concerned.

Wrapper cut-off device

For the construction and details of this device the aforesaid specification will also furnish the necessary information, bearing in mind that the only difference resides in the disposition and function of the knife itself. While in the last previous case, as Fig. 22 of said specification shows, the stationary part of the cutting device, viz: the ledge 108 over which the wrapper glides, is uppermost and the knife blade 110 cuts it from below, this arrangement is now reversed and the knife 110 in the present Fig. 1 swings down upon the wrapper strip, passing across a narrow trench 108' between the plate 71 and the

wrapper table 13, (Figs. 1 and 2), so that in this respect the device resembles former arrangements, no claims being made as to novelty. In abbreviated terms the construction of the cut-off mechanism is as follows: The knife blade is pivoted at 109 on a bolt 114 passing through a hollow rocking shaft 112, journaled over and crossing the clutch shaft 58. At the other end of this bolt is threaded a nut 117, cushioned on a spring 118, by means of which the knife blade may be tightened in relation to the trench edge, to insure a prompt shearing action.

The blade 110 is clamped to the one-arm lever 111 by means of pin 113, while the lever is linked to the rod 121 by means of the universal joint 120. The rod is actuated by a cam lever and cam on the main cam shaft in well known manner which, forming no claimed part in my present application, does not need to be further illustrated.

Band and label feeding device

It is this device and the pneumatic conveyor with which it cooperates and which will be dealt with subsequently, that are concerned with the novel and patentable features claimed in this application and their construction will therefore be described minutely in detail. The band magazine, consisting of two guide brackets 3 and 4, forming rectangular channels, as well as the label magazine, comprising a dish-like support 24 with two semi-circular guides 25a and 25b, fastened therein, are supported on an upper platform 6 which in turn is mounted by means of two columns 7 and 8 on a larger platform 9 that carries also the aforementioned bearing frame 55, together with the whole wrapper feeding device, so that by means of the clamp bolt 123 the same can be adjusted horizontally and aligned with the band feed and the adjoining wrapper conveyor, as aforesaid. This main platform itself is supported by a bracket 10 which either forms an integral part of the main machine frame 1 or is bolted thereto in any convenient way. By means of circular apertures provided in the platform 9, the latter also serves as a pivotal support and guidance for the band picker 11 and the adjoining label picker 12, to be described later. The wrapper table 13 is likewise supported on this platform 9.

The upper platform 6 (see Figs. 1 and 2) is a lengthy bedplate, shaped symmetrical to the center line of the band and label magazines, except that the rear end, adjoining the wrapper feed device, is cut obliquely at 15 and the left rear corner is squarely cut away at 16 to provide clearance for the knife 110. The right rear corner is bolted onto the top of rear column 7, and the front portion of the plate is reduced in width to form a tongue 6', to be bolted onto the front column 8. On the centerline of symmetry, the plate 6 is cut out, to form discharge apertures for the superimposed magazine structures, a larger cutout 17, substantially in the shape of a wide slot, to permit the largest size of cigar band to pass through, and a circular cutout 18 for the label magazine support 24, to be seated therein. The two band magazine guide brackets 3 and 4, almost symmetrical in structure and oppositely arranged, form each an upright rectangular channel, as may best be seen from Figs. 1 and 2 with a blocklike extension 3a and 4a respectively at the base. To the upper surface of the bedplate 6, parallel to the outer edge, is securely fastened a finished ledge or guide rail 19 which these base

extensions, saddle-like, embrace and along which they can be adjusted and clamped tight by means of the knurled set screws 20 and 21. As the feet of the upright channel portions 3 and 4 are slidably guided within the slot 17, it is apparent that the distance between the upright channels can be adjusted in this manner to fit any likely size of cigar band 23. The cross sections through the opposite channels differ in widths, according to 10 the customary shape of cigar bands used. This is the main deviation from the structural symmetry of both guide members; moreover, exchangeable sets of different guide members 3 and 4 may be used to accommodate various makes of 15 cigar bands.

Fig. 17 shows a modification of the magazine just described, or rather, it does not show a cigar band magazine, but a magazine for medallions, such as spoken of before.

20 The two guide brackets 160 and 161 are adjusted in closer proximity, and their cheeks 160b and 161b have to be shaped in conformity to the contour of the medallion which they are supposed to hold. The base extensions 160a and 161a 25 are advantageously turned toward the outside to permit a closer adjustment of the two brackets. Otherwise the construction is analogous to the one just described.

The semi-circular guides 25a and 25b of the 30 label magazine can be formed from the split halves of a tubular casting, flaring out somewhat at the top, extending downwardly beyond aperture 18, and formed with two lateral base extensions, 25m and 25n. The circular dish-like base or pedestal 35 24, which is shown in detail in Figs. 15 and 16, comprises a circular short shank 24a, which is inserted into the circular aperture 18 of the base plate 6. Above this aperture extends the circular flange 24b which around the edge is grooved, as 40 at 24g, to facilitate lifting or turning the member 24 with a spanner or wrench. The middle portion of the casting is apertured by a cutout 24c, the shape of which is best described as formed by two oval slots intersecting each other at right 45 angles. Around the top opening of this cutout, a pair of walls or ridges 24d and 24f is provided which partly borders the central cutout with two opposite arcs and partly forms sliding guides for the base extensions 25m and 25n of the semi- 50 circular guides 25a and 25b, aforementioned. By two set screws, passing through slots in these extensions and tapped into the casting 24, as indicated at 24s and 24t, the semi-circular label guides 25a and 25b can then be spaced apart at the right 55 distance to accommodate any small stack of labels shown at 22, Fig. 1. On the underside of the circular flange is provided a dowel pin 26 which fits into any of three dowel pin holes 26a, b or c, drilled in the base plate 6 and spaced at 45° radi- 60 ally around the center of the opening 18, as indicated in Fig. 1. It is obvious that by this arrangement the label magazine can be set at different angles, and as will become apparent from a later description of the band and label pickers, 65 the consequence of such an adjustment is that the small label can be placed in either of three different positions on the wrapper, either so that it is seen running across the cigar, similar to the band, or running in a longitudinal direction or 70 finally in a diagonal direction. Fig. 17 shows the label magazine in such a position that it would deliver the label, so as to run in an axial direction of the wrapper.

The labels as well as the cigar bands are stacked 75 in their respective magazines with their printed

face upside, as indicated in Fig. 1. To prevent a premature spontaneous discharge or dropping out of the bands or labels at the bottom, the two opposite inner ends of the channel guides 3, 4, 25a and 25b near the bottom edges are provided each 5 with a short pin point, protruding into the path of said bands or labels respectively, not especially illustrated, as this feature is well known from former band magazine constructions.

Pneumatic band and label picking device

10

This device consists of a triplet plunger; i. e., a compound plunger comprising two superimposed yokes 27 and 28, coupled together by three piston-like members, two outer tubular shorter 15 members 30 and 31, and a longer solid middle member 32, all three members arranged in a row and guided in a straight vertical reciprocating course by three juxtaposed circular cutouts 30a, 32a and 31a in the platform 9. (See 20 Figs. 2, 3, 9, and 10.)

The middle member 32 consists of a rod, lengthened downwardly below the bottom yoke 28 and is slidably guided in a sleeve 35 which can be made in form of a bracket, integrally built with the main frame of the machine. In the tubular members 30 and 31 are journaled two shafts 33 and 34, themselves partly perforated to form conduits for the suction device, as will be described later. These shafts project above and below the yokes 27 and 28, and on each of these projecting ends is fixedly attached a crank-shaped arm, though differently formed in each case, 36, 37, 38, and 39 respectively. The two lower arms 38 and 39 are furthermore coupled 30 together by a yoke 40, and it will be understood, that when these two lower arms are now rocked or swung back and forth in a circular arc, the two upper arms—which are not necessarily set at the same angle to the shafts as the lower ones—will execute a swinging motion through 35 an arc of the same degree. It will also be apparent that it is necessary to only move one of the lower arms through an arc of say 45°, in order to have all four arms execute a swing of 45° 40 simultaneously. This can best be understood by a study of Figs. 9 and 10 in comparison.

The lower rear arm 38 consists of a short cylindrical sleeve, securely fastened to the shaft 33, and two arms 38a and 38b, forming a bell-crank 50 55 of about 45°, integrally cast with the sleeve and having its fulcrum in the axis of said sleeve. The arm 38b (Fig. 9), which is solid, is pivotally linked to the yoke 40, while the arm 38a (see also Fig. 2) is perforated and carries a hose connection nozzle 41, to the lower end of which a rubber tube 42 can be attached which leads to a pneumatic suction valve, not shown. Both the arm 38a and the shaft 33 are provided with an air conduit 38c, terminating in the crank-shaped upper arm 36. This upper arm (Figs. 9 and 10) is a one-armed crank-shaped lever, comprising a short cylindrical sleeve 36a, securely fastened to the protruding top end of the perforated shaft 33, a short horizontal arm 36c, and a sleeve-shaped support 36b into which is inserted a tubular fitting 43, shaped in upright T-form and illustrated in Fig. 12. The vertical shank 43a is cylindrical, but the horizontal cross piece 43b has a rectangular prismatic form, best shown in 70 Figs. 9 and 10. In the top surface are provided two apertures 44a and 44b which form the outlets of the hollow interior of the fitting, and between the two outlets the surface is slightly raised to form an apex or ridge 45. The perforations of 75

the members 41, 38, 36, and 43 form a continuous air duct, and it is evident that any cigar band or piece of paper, if laid across the two apertures 44a and 44b, would be forcibly attracted and held fast, if a suction or vacuum were produced within the air duct. At the same time, if this suction head were applied to the underside of a stack of cigar bands, the latter at the moment of detachment would be slightly bent across the ridge 45, which therefore helps to separate the extreme ends of the band from the stack and slip them over the pin heads in the channel guides, mentioned before. The prismatic head 43b is held in proper angular position by a rectangular border 36r, forming a ridge, integral with the support 36b. A little set screw 36s, set against the shank 43a further helps to keep the fitting 43 in fixed position.

If the rectangular border on the suction head 36 is so arranged that the prismatic crosspiece 43b lies in the axis of the band magazine 3-4, as Fig. 9 indicates, and a cigar band, outlined in dot and dash lines, is picked off, then, after the band picker 36 is swung through an arc of 45°, the cigar band will have turned about 45° also, being placed right across the center line of the path along which the wrapper sections will travel, said centerline leading directly into the cigar banding and wrapping position between the centering jaws 66 and 67, as Fig. 1 illustrates.

The label picking arrangement is similar and analogous to the band picker just described.

The lower front arm 39, corresponding to the arm 38 differs from the latter principally in that the cylindrical sleeve, fastened to the hollow shaft 34 has only one solid arm 39b, pivotally linked to the other end of the yoke 40 which therefore couples the two arms 38b and 39b, so as to perform parallel movements. The rubber tube 52 is directly attached to the hose connection nozzle 51, (see Fig. 2) inserted into the tubular shaft 34, analogous to the nozzle 41, and the air duct, provided therein, leads straight into the upper crank-shaped picker arm 37 which corresponds to the arm 36, formerly described. These picker arms are similar in design and principle, except that the sleeve-shaped support 37b into which is inserted the tubular fitting 53, has not a rectangular head but is shaped as a round collar which supports the tubular fitting 53, shown in detail in Fig. 11. This fitting has a straight central bore 53d, plugged at the bottom and having a side outlet 53s, adapted to register with the air duct in the picker arm 37, but this side outlet 55 is slotted in a circumferential direction, wide enough to provide communication between the duct portions at three different positions, as will be explained later. Above the shank 53a is provided a circular flange 53f, forming a seat for the fitting upon the upper face of the collar 37b and diametrically across this flange runs a little oblong and flat block 53b, which approximately covers the outline of the label to be fed by the magazine. In this instance the top surface 65 resembles a short oblong with semi-circular ends (see Figs. 9 and 10) upon which the label (shown in dash and dot lines) can be placed without projecting over the periphery. The air duct has its circular outlet 53h in the center of this surface. The manipulation and transfer of the label from the bottom of the magazine into the wrapper path is quite analogous to that of the cigar band, formerly described.

As an inspection of Fig. 10 will show, the top 75 of the collar 37b has three radially disposed

grooves 37', 37² and 37³, spaced at 45° apart from each other. A little dowel pin 53p passing through the flange 53f (Fig. 11) fits into any of these grooves according to the angle, at which the fitting 53 is inserted into the sleeve or collar 37b. Thus it is possible to predetermine the final application of the label, either across the cigar, or parallel or diagonal to its axis.

Driving means for band and label pickers

It may be remarked in advance that the band and label picking mechanism has to execute a compound movement; in addition to an alternating swinging motion of the crank-shaped arms through an arc of 45 degrees, the triplet plunger has to perform a reciprocating vertical motion, the different phases of the two kinds of motion interlocking with each other in the following way: When the swinging arms are in the position indicated by Fig. 9 and the two suction heads 43 and 53 have each simultaneously abstracted a band and a label respectively from the magazine stacks, the plunger with the yokes 27, 28 and the pickers descend, while during the descent the arms begin a swing through the 45 degree arcs. The shafts 33 and 34 turn in a counter-clockwise sense, seen from above. When this swing is half completed, the plunger has reached its deepest position and begins to ascend again during the second half of the swing; when the top of the plunger has reached the underside of the wrapper table, the arms are in the position indicated by Fig. 10, whereupon the pneumatic suction on the band and label is interrupted and both are carried away together with the wrapper in a manner yet to be described. Then the combined motions of the arms are repeated in the reversed order; i. e. the shafts 33 and 34 revolve in a clockwise sense while the plunger descends and again ascends so that the pickers return to their original position underneath the magazines whereupon the pneumatic suction is turned on again and the cycle begins anew.

While the horizontal swinging motion is imparted to the lower rear arm 38, which in turn imparts it to the lower front arm 39, the vertically alternating motion is imparted to the plunger through a lever connection attached to the lower yoke beneath the piston 32 in the center of the plunger. The different driving connections are actuated from the main cam shaft 60 by two cams 63 and 64 which act upon two rollers 63a and 64a respectively. Cam shaft 60 is shown here as being located near the hopper end of the machine (Fig. 5); this, however, may depend upon the general arrangement of the wrapping machine and may vary. Roller 64a is journaled in the forked end 68f of a bell crank 68, fulcrumed on a stud 69, suitably held by the main frame 1 of the machine. This bell crank is shown as consisting of a casting with a wrought iron extension 68a bolted to the free arm, but it can just as well be made of one integral piece.

The yoke 28 has, surrounding the solid middle guiding rod 32, which fixedly connects it with the upper yoke 27, a downwardly and laterally protruding extension 70 (Figs. 2, 3, and 5) which is formed as a forked bearing. In this bearing is pivotally jointed the connecting link 71 to which the end of arm 68a is similarly attached. It is obvious then, that if the bell crank 68 is rocked by the action of the cam 64, it lifts the link 71 and through this the plunger which is guided in the platform 9 and the sleeve 35. A spring 72, fastened with one end to the main frame and the

other to the bell crank tends to turn the latter in a sense opposite to the action of the cam 64.

The movement, actuated by the cam 63 for the horizontal swing, is not directly imparted to the arms of the pickers, but first to a countershaft 74 near the delivery end of the machine by means of the forked lever 75 which is pivotally suspended on the stud 76 in the main frame and carries the roller 63a, and by means of the long connecting rod 90 which is linked to the bracket-like crank 91, keyed or otherwise rigidly fastened to the countershaft 74. The latter whose length is determined by the arrangement of the machine, may in many cases simply resemble a long stud held in a bearing bracket 73, which is bolted to the main frame 1. The crank 91 has two bearings in its arm, positioned at different leverages from its fulcrum and adapted to carry laterally projecting studs, one fixed circular bearing 91a, 20 which carries the stud 93, and one slotted bearing 91b in which the stud 95 may be adjustably bolted. The connecting rod 90 is journalled on the stud 93 by means of its T-shaped head 94 which is rotatably embracing said stud. The connecting rod 99 which transmits the rocking motion of the crank back to the lower rear arm 38 of the picker device is jointed to both these elements by means of universal joints, one, indicated by numeral 96, linking it to stud 95, the other, called 97, linking it to the projecting top end of the hose connection stud 41 in the arm 38 (see Figs. 2 and 3). The construction of such universal links is well known, and therefore does not need any detailed description which moreover can easily be deduced from the drawings. This lever connection arrangement makes it apparent that not only the rocking motion, initiated by the cam 63, is thus transmitted to the band and label picker arms but its amplitude is also increased in the adjustable proportion, provided by the studs 93 and 95, carried by the crank 91. The universal joint connections are necessitated by the varying position of the plunger. The return motion of the connecting rod 90 to its normal position is caused by the coil spring 104, which is tensioned between two pins, one 104a on the connecting rod 90, the other, 104b, fastened to the machine frame.

Wrapper table and heating device for attaching label

The wrapper table 13 which was already mentioned is a flat brass plate, well polished on both sides, substantially of rectangular cut and with the rim 13a where it adjoins the plate 11 beyond the knife trench '108' tapered down to a sharp edge, adapted to pick up the wrapper when the latter glides over from the plate 11 (see Fig. 2). The height of the horizontal table is so arranged that the sharp edge is just a trifle below the upper surface of plate 11. Approximately, though not necessarily, this is also on the level with the bottom of the magazines, as any difference in respective heights and consequent variations in the upward motions of the plunger can be taken care of by the way the cam 64 is shaped, as Fig. 5 indicates, the two opposite peaks on the circumference being of different height. The right hand front corner of table 13 has a lateral extension 13b which is supported by the column 8 (see Figs. 1 and 2), the latter having an offset at the proper height and a sleeve separator 8b between the extension 13b and the platform 6, while the latter is clamped down by a nut over the threaded end 8a. The rear end of the table is

supported on a special column 105 which is mounted on the platform 9. The table itself has near its longitudinal edge toward the delivery end of the machine two large circular openings, the upper edges of which are chamfered off, as indicated at 13B and 13L in dot and dash lines (see Figs. 1, 9, and 10). These openings are so located that they are concentrical with the centers of the suction heads for the label and band pickers when these are swung over into feeding position. When these suction heads, bearing the cigar band and the label respectively, reach their highest position, the cigar band just touches the underside of the table, while the label due to a slight difference in the height of the suction heads, is even carried a trifle higher, so that it touches the underside of the cellophane wrapper which in this moment happens to lie on top of the table 13. In this position the label is ready for the action of the heating device which will now be described.

The latter is a small electrically heated reciprocating press (see Figs. 1, 3, and 13), comprising a rocking shaft, supported by two bearing brackets, a cylindrical heating element mounted at the end of two rocking arms, fulcrumed on said shaft, and two heating dies, attached to said element.

The bearing brackets 106 and 107 are simple rectangular brackets, bolted with their horizontal leg onto the platform 9 near the edge, adjacent the drive for the wrapper feed rollers, and having in the top of their upright leg a round eyelet for journaling the ends of the shaft 115 therein. On this shaft is adjustably fixed by means of the set screw 116a, the sleeve 116, from which near its ends project the two lateral arms 124a and 124b, terminating in two annular die holders 125a and 125b respectively. Across the ends of these arms and forming an integral brace for them is provided a cylindrical drum 125 in which is mounted a heating coil 126, receiving current through a two-strand conductor 127, leading into one end of the drum (see Figs. 13 and 1). This may be attached to a lamp socket or the like. The dies 128 which can be fixedly inserted in these die holders and of which one is shown in detail in Figs. 13 and 14 are of the self-leveling type, that is: from a cylindrical shank 128a which is fitted fixedly into the bore of the die holder 125a or 125b respectively, by means of a washer 128c and tap screw 128b, is at the lower end pivotally suspended and balanced by the pin 129, a cross piece 128d (Fig. 14). This is substantially a longitudinal stamp, tapered laterally toward the ends and grooved along its top, so that a cross section through it resembles an upright V. The lower end of the aforementioned shank 128a has a short cross arm 129d, integral with the shank and loosely fitted into the groove of the crosspiece 128d by means of the pin 129. Between the bottom of the groove and the arm 129d is provided enough clearance for the crosspiece 128d to accommodate itself to the supporting surface (53b of the label support in this case) if the arm 124a or 124b with die holder 125a, b descends upon it. The heat created in the cylindrical drum 125 by the coil 126 is imparted to the depending dies, and when, as explained before, the band picking arm 31, carrying the label 22, has swung over to the opening and raised the label into intimate contact with the wrapper lying over and covering said opening, the descending die 128 will impart its heat to the underlying wrapper portion and the label underneath it. These labels, on their printed surface, which as said before, lies upper-

most, are impregnated with a special dry adhesive lacquer which when heated, becomes glutinous. Consequently, the label is firmly attached to the underside of the superimposed wrapper, in whatever position it may be presented to it, and when immediately after this the pneumatic suction is released, the wrapper together with the glued-on label can be conveyed toward the wrapping and banding mechanism. As will be seen from Fig. 1 especially, there are two arms with die holders provided, one for each opening 13B and 13L respectively, though, if a cigar band is used, only one of them, i. e. 125b for 13L, is needed and consequently fitted with a die 128, while the other die holder works idle. If, however, as said before, a medallion only or a medallion plus a label is used, and if then the present band magazine is replaced by a medallion magazine, such as is shown in Fig. 17, then another suitable heating die, large enough to cover the medallion, but otherwise of the same construction as that shown in Fig. 14, is inserted into the die holder 125a.

The actuation of the heating device is carried out in the following way. The sleeve 116 with its projecting arms 124a and b is fixedly attached on the rocking shaft 115, as said before. Furthermore, in similar manner, two collars 130, 131 and a rearwardly extending arm 132, best shown in Fig. 3 are fixed upon this shaft. The collars have each a short forwardly projecting arm 130a and 131a with a lateral pin extending from it, while the arm 132 has at its rearmost end also a lateral extension 132a. The latter is so disposed that it extends underneath the one-armed lever 111, formerly described, which as will be remembered, actuates the knife blade 110 and is itself rocked by the vertical rod 121. Consequently, simultaneously with the up and down motions of the knife, the shaft 115, together with the arm 132, the heating drum 125 and the pin-carrying arms 130a, 131a are rocked up and down, so that the impression of the heated die is synchronized with and governed by the knife action. A counterweight 133, which is separately attached to the heating drum 125, helps to increase the pressure of the die and to assure the downward swing of the arms 124a, b.

Between the electrical heating device and the wrapper table 13 is operatively provided a flap or loosely hanging plate 135 (see Figs. 1 and 3). This is a thin rectangular plate, adapted to cover about the area of a wrapper, with two circular cutouts 135a and 135b for the dies of the heating device, and when this flap is dropped upon the wrapper and the underlying table 13, these cutouts are concentric with the circular openings 13L and 13B. The flap is loosely hinged upon the rocking shaft 115 by means of two integral rib-like arms 135c and 135d, embracing the shaft, adjacent to the collars 130 and 131 with two annular bearings. As Fig. 1 shows, the two lateral pins, extending from the members 130 and 131 are so arranged that they will lift and—vice versa—drop these arms and the flap with them in conjunction with the movements of the heating device. The purpose of the flapping plate is to keep the wrapper straightened out against the table 13 while the heating die is impressed upon the label. The clearance between the pins and the flap arms is so adjusted that the flap comes to rest upon the wrapper a fraction of a second before the die strikes the wrapper and the label underneath. The flap and the die is released just before the wrapper is moved along by

the pneumatic conveyor which is about to be described presently.

Pneumatic wrapper conveyor

This conveyor is identical in its actuating and conveying means with the band conveyor shown in the earlier application, Ser. No. 713,116, but while in this former application, the conveyor only carried a band from right to left toward a wrapper,—in the present device, it carries a wrapper together with a band or a wrapper alone, to which a medallion and a label is fixedly attached, from left to right, or from a point where band and wrapper, or medallion, label and wrapper are brought together, to the wrapping position. Another feature, for which patentable novelty is claimed, is this. While in the former device, the holding means consisted of a mechanical gripper which gets a hold of the band at the start of the course and releases it at the end, pneumatic suction alone is used presently, not only to carry the band, if any band is used, but likewise the wrapper itself.

We will first shortly describe those parts which are similar to the former construction.

A horizontal rail 150, spans the path along which the wrappers are travelling and is freely suspended on the brackets 154 and 155 (see Figs. 6 and 7). On this rail is slidably mounted the frame 153 which partly surrounds the rail in the manner described in the above mentioned application, and is itself attached by means of the lug 151 to a link of the sprocket chain 164 by which it can be reciprocatingly drawn back and forth over the rail 150. The horizontal run of this chain is guided over the two sprockets 165 on stationary stud 166 at the front and sprocket 167 on stud 168 at the rear of the machine frame 1. The downward extending portion of the chain at the rear supports a counterweight 169 which serves to pull the chain and frame 153 automatically from the wrapping position D to the wrapper receiving position when the pull at the front end of the chain is released. The front end of the chain goes over idler 163 and is then looped around the floating sprocket 170, freely rotatable on stud 171, secured in the free end of curved lever 172 which is loosely mounted on rock shaft 89. This lever has a lateral ear or extension 173 which carries a stud 174 on which is linked a connecting rod 175, leading to a stud 176, the latter being mounted eccentrically on a disk 177 which is rotating at the end of a shaft 178, journaled in frame 1 and driven by a chain and sprockets from the main cam shaft of the machine (not especially illustrated). The rotation of shaft 178 and the disk 177 imparts a reciprocating swing around shaft 89 to the loosely mounted lever 172 which thereby swings sprocket 170 in an arc around and below the shaft, thereby pulling the chain and the attached conveyor frame toward the wrapping position, while on the return swing the weight 169 helps to return the frame together with the chain toward the wrapper receiving position.

Fixedly fastened to rocking shaft 89, either separately or forming an integral extension of lever 172, is a lever arm 88 which carries at its free end on a stud 87 the floating sprocket 86. The chain 79, formerly mentioned, which operates the wrapper feed from the cellophane roll, is fastened with its extreme end to a bracket 84 by means of stud 83. This bracket is fastened to the frame 1 by screws 85—85. This chain is looped over the floating sprocket 86, passes upwardly over the idler 71

sprockets 137 and 138, thence over the sprocket 78 (see Fig. 2) and goes to the spring drum 80, as described in the beginning.

Therefore the reciprocating movement of this 5 wrapper feed drive is also actuated by the rocking shaft 89 and synchronized with the conveyor drive.

While the hitherto described parts of the wrapper conveyor more or less closely resemble the conveyor drive, described in specification, Serial No. 10 713,116, the rest of the construction is modified, so as to adapt it for a pneumatic gripping action.

The upper part of the frame 153 is formed as a 15 sliding runway for the suction chamber 140. At each end it has a pair of upwardly extending lateral ears, 156a and b at the rear end and 157a and b at the front end. Between these ears are fixedly held two brass blocks 158 at the rear and 20 159 at the front which form stops for the sliding motion of the suction chamber and furthermore anti-friction bearings for the stop members, as will be explained later. On this runway is slidably mounted a hollow longitudinal box with a 25 separate but ordinarily fixedly attached lid.

The lid 149 is a flat plate, chamfered down on its rear end to a lower level, as shown at 149a, and 30 perforated along one of its longitudinal edges which adjoins the course the wrapper takes; two rows of small staggered holes 149b, intended to take a sucking grip on the wrapper, on the higher level, and a pair of larger holes 149c, on the lower level, as can best be seen on Fig. 7. These latter holes are intended to take hold of the band, which, 35 as will be remembered, is delivered at a lower level, being underneath the wrapper table.

The lower part 140a of the box-like suction chamber has a length about $\frac{1}{4}$ to $\frac{3}{8}$ of an inch less than the available runway between the stops 158 and 159 and is cored or grooved out between 40 its solid ends 140c and 140d. Within the latter, which is the front end, is fixedly secured the end of a tubular stem 141 which also slidably passes through the aforementioned stop 159. At the 45 outer or free end the stem carries a nipple 142 to which the suction tube 143 is attached. The other end of this tube is connected to the air valve which controls the suction of the conveyor as well as that of the band and label pickers. On the 50 stem is furthermore fixedly seated a collar 144 with a downwardly extending ear 144a which contacts with a stop pin 145 on the rail 150 when the conveyor frame moves to its extreme position at the wrapping station D.

Secured to the underside of the suction chamber at the rear end is the bearing plate 146 which 55 passes through the rear stop 158. When the conveyor reaches its utmost rear position at the wrapper receiving end, the extant end of this plate contacts with another stop pin 147 (see Figs. 6 and 7). A spring actuated tension button 148, 60 located in the stop 158 presses slightly upon the bearing plate and prevents any spontaneous dislocation of the plate together with the suction chamber, unless moved by the impact of the stop pins.

The function of these stop pins in cooperation 65 with the plate 146 and the collar 144 is similar to the limit stop arrangement of the conveyor described in specification, Serial No. 713,116. When the frame 153 with the bearing plate protruding, as shown in Fig. 6, reaches its extreme rear position, and the suction chamber is directly beneath the wrapper (and the band), and the plate 146 70 strikes the stop pin 147, the suction chamber 75

remains stationary while the frame continues for a short distance to move on until it is stopped by the chain and lever mechanism, above described. The holes 149b are then directly beneath one edge of the wrapper, while the holes 149c are beneath 5 the band. While the suction chamber is stationary, the air valve shuts off the suction on the band and label pickers and creates suction in the chamber 140, causing the band and wrapper to adhere to the same. The conveyor frame together with the chamber, the band and the wrapper then moves to the right until the downward extending ear 144a strikes the stop pin 145. This 10 stops the movement of the suction chamber itself, while the conveyor frame still moves a little further until its actuating mechanism brings it to rest. During this short period the air valve cuts off the suction in the chamber and supplies in 15 turn suction to the band and label pickers, while the band and wrapper, released from the suction chamber, are carried up together with a bare cigar, rising from below into the wrapping mechanism.

Mode of operation

After the magazines are filled, either with a 25 stack of cigar bands and labels or with a stack of medallions and labels, the exhaust pump is set in motion and the machine clutch is released.

The wrapper feed W feeds out a wrapper of the predetermined length, while the band (or medallion) and label pickers swing to a position underneath their respective magazines. The vertically moving triple plunger 30, 31, 32 moves up, bringing the pickers against the lowermost band (medallion) and label, the suction valve opens, 30 creating a vacuum in the pickers and abstracting a band and a label from the magazines; the plunger is lowered, the pickers swing over beneath the now stationary wrapper, the plunger moves up 35 slightly, bringing the band to the level of the suction chamber 140, and the small label up against the underside of the wrapper. The knife begins its downward movement, allowing the clamping plate or flap 135 to rest on the wrapper, supported by the table 13. The knife continues 40 its downwardly cutting movement, allowing the heater unit to contact the upper surface of the wrapper, directly over the small label (and eventually over the medallion), the heat fuses the coating of the wrapper and label (and medallion) so that it firmly adheres to the underside of the 45 wrapper. At this time, the suction chamber being still at rest, the air valve closes, cutting off the suction in the band and label pickers, while immediately afterwards creating suction in the suction chamber. The triple plunger with the pickers are then lowered, the knife moves up, raising the heating unit, and afterwards the clamp plate 50 also. Then the conveyor frame with the suction chamber carrying the wrapper (and eventually also the band) moves over to the right toward the wrapping position, until the suction chamber collar 144 strikes the stop 145 and comes to rest. Then the air valve shuts off the suction in the 55 chamber, while supplying new vacuum to the band and label pickers. The wrapper and band, released from the suction plate 140b is carried upward by the cigar into the wrapping mechanism, and the whole cycle of operation repeats itself.

It is obvious from the foregoing detailed description of my invention that I have produced a 60 novel wrapper feeding mechanism which optionally will apply a transparent wrapper to a cigar together with a band between said wrapper and 65

the cigar or a wrapper alone with the center-piece of the band,—the medallion—firmly attached to the underside of the wrapper, while in addition in both cases a small pad or label is attached to the underside of the wrapper, as illustrated in Figs. 18, 19, and 20. All three attachments, cigar band, medallion and label, are visible and readable through the wrapper, and when the wrapper is removed from the cigar, whatever is firmly attached to it, the label and eventually the medallion too is removed and may be discarded at the same time.

Thus all the enumerated objects of the invention are obtained in an efficient, economical and simple manner and all the mechanical devices described are coordinated to automatically and synchronously perform the functions required.

In accordance with the provisions of the patent statute, I have described my invention, but I desire it understood that it is not confined to the particular form shown and described, the same being merely illustrative, and that the invention can be carried out in other ways without departing from the spirit of my invention, and therefore, I claim broadly the right to employ all equivalent instrumentalities coming within the scope of the appended claims and by means of which, objects of my invention are attained and new results accomplished, as it is obvious that the particular embodiments herein shown and described are only some of many that can be employed to attain these objects and accomplish these results.

Having now described my invention, what I claim and desire to secure by Letters Patent, is:

1. The combination with a cigar banding and wrapping machine, adapted to apply a cigar band around a cigar and wrap a transparent wrapper over it, so that the cigar band can be seen and read through the wrapper; a wrapper holder, a label holder, of pneumatic means to deliver a cigar band together with a wrapper toward a cigar banding and wrapping position, said means comprising a reciprocating carriage, means to transfer a cut-off wrapper portion from the wrapper holder and place it on top of said carriage, pneumatic means to convey a cigar band from a magazine to the top of said carriage, means to place a cut-off wrapper portion from a wrapper supply source on top of said band suction means operatively connected with said carriage to hold the band in fixed relationship to the wrapper on said carriage during transit, and vacuum controlling means to release the band and wrapper when the carriage has reached the banding and wrapping machine.

2. The combination with a cigar wrapping machine adapted to wrap a transparent wrapper, carrying a separate label, over a cigar, so that the label can be seen and read through the wrapper; a wrapper holder, a label holder, of pneumatic conveying means to place the label into fixed relationship to the underside of the wrapper, means to firmly attach the label to the wrapper, and pneumatic means to carry the wrapper, with the label attached to it, toward a cigar wrapping position, means to transfer a cut-off wrapper portion from the wrapper holder and place it on top of said pneumatic conveying means, means to fuse said label to the wrapper and means to fold said wrapper around the cigar.

3. In a cigar wrapping machine, adapted to wrap a transparent wrapper, carrying a separate label underneath it around a cigar, a wrapper holder, a label holder, a conveyor adapted to carry

a wrapper by pneumatic suction means toward a wrapping position, means to transfer a cut-off wrapper portion from the wrapper holder to the conveyor, separate pneumatic suction means to transfer a label from the label holder to the underside of the wrapper portion, heating means to fuse the transferred label fixedly to said wrapper, and air controlling means to alternately open and cut off the pneumatic suction means in the conveyor and the label transferring means.

4. In a cigar wrapping machine, adapted to wrap a transparent wrapper, carrying a separate medallion underneath it around a cigar, a wrapper reservoir, a medallion reservoir, a conveyor adapted to carry a wrapper by pneumatic suction means toward a wrapping position, means to transfer a cut-off wrapper portion from the first reservoir to the conveyor, separate pneumatic suction means to transfer a medallion from the second reservoir to the underside of the wrapper portion, heating means to fuse the transferred medallion fixedly to said wrapper, and air controlling means to alternately open and cut off the pneumatic suction means in the conveyor and the medallion transferring means.

5. In a cigar wrapping machine, adapted to wrap a transparent wrapper, carrying a separate medallion and label underneath it, around a cigar, a wrapper reservoir, a medallion reservoir, a label reservoir, a conveyor adapted to carry a wrapper by pneumatic suction means toward a wrapping position, means to transfer a cut-off wrapper portion from the first reservoir to the conveyor, separate pneumatic suction means to transfer a medallion and a label from the second and third reservoir to the underside of the wrapper portion, heating means to fuse the transferred elements fixedly to said wrapper, and air controlling means to alternately open and cut off the pneumatic suction means in the conveyor and the label and medallion transferring means.

6. In a cigar banding and wrapping machine, adapted to apply a cigar band around a cigar and wrap a transparent wrapper, carrying a separate label, over it, so that the cigar band and the label can be seen and read through the wrapper, a wrapper reservoir, a band reservoir, a label reservoir, a conveyor adapted to carry a band and a wrapper, covering it, simultaneously by pneumatic suction means toward a banding and wrapping position, means to transfer a cut-off wrapper portion from the first reservoir to the conveyor, separate pneumatic suction means to transfer a band and a label from the second and third reservoir respectively to the underside of the wrapper portion, heating means to fuse the transferred label fixedly to the underside of said wrapper, and air controlling means to alternately open and cut off the pneumatic suction means in the conveyor and in the band and the label transferring means.

7. In a machine of the class described, adapted to wrap a transparent wrapper carrying a separate label around a cigar so that the label can be seen and read through the wrapper, a wrapper and label feeding mechanism, comprising means to feed a web of wrapping material in the direction of a wrapping mechanism, means to feed an individual label to a position underneath the portion of said web which will form the wrapper of a single cigar means to fixedly attach said label to said portion of the web, means to sever said portion from the web, and means to convey said severed portion with its affixed label to a wrapping mechanism.

8. In a machine of the class described, adapted to wrap a transparent wrapper carrying a separate label around a cigar so that the label can be seen and read through the wrapper, a wrapper and label feeding mechanism comprising means to feed a web of wrapping material in the direction of a wrapping mechanism, means to feed an individual label to a position underneath the portion of said web which will form the wrapper of a single cigar, means to fixedly attach said label to said portion of the web, means to sever said portion from the web, and pneumatic means to convey said severed portion with its affixed label to a wrapping mechanism.

9. In a machine of the class described, adapted to wrap a transparent wrapper carrying a separate label around a cigar so that the label can be seen and read through the wrapper, a wrapper and label feeding mechanism comprising means to feed a web of wrapping material in the direction of a wrapping mechanism, adjustable means to feed an individual label in any one of a plurality of predetermined positions relative to and beneath the portion of the web which will form the wrapper of a single cigar, means to fixedly attach said label to said portion of the web, means to sever said portion from the web, and means to convey said severed portion with its affixed label to a wrapping mechanism.

10. In a machine of the class described, adapted to wrap a transparent wrapper carrying a separate label around a cigar so that the label can be seen and read through the wrapper, a wrapper and label feeding mechanism comprising means to feed a web of wrapping material in the direction of a wrapping mechanism, means to position an individual label at a portion of the web which will be within the boundaries of an area which will form the wrapper of a single cigar, means for heating the web at the point at which the label is positioned, means to sever the web, and means to convey said severed portion, with its affixed label, to a wrapping mechanism.

11. In a machine of the class described, adapted to wrap a transparent wrapper carrying a separate label around a cigar so that the label can be seen and read through the wrapper, a wrapper and label feeding mechanism comprising means to feed a web of wrapping material in the direction of a wrapping mechanism, means to feed an individual label to a position underneath the portion of said web which will form the wrapper of a single cigar, means to fixedly attach said label to said portion of the web, means to sever said portion from the web, and a pneumatic conveyor comprising a reciprocating carriage to convey said web with the attached label to a wrapping mechanism.

FRANCIS X. MALOCSSAY. 30
